UNITED STATES PATENT OFFICE.

JOSEPH HUNTER DICKINSON, OF LARCHMONT, NEW YORK, ASSIGNOR TO THE
AEOLIAN COMPANY, A CORPORATION OF CONNECTICUT.

AUTOMATIC MUSICAL INSTRUMENT.

1,359,040.

Specification of Letters Patent. Patented Nov. 16, 1920.

Application filed August 28, 1918. Serial No. 251,784.

To all whom it may concern:

Be it known that I, JOSEPH HUNTER DICKINSON, citizen of the United States, residing at Larchmont, New York, have invented 5 new and useful Improvements in Automatic Musical Instruments, of which the following is a specification.

My present invention relates to means in 10 automatic pianos and like instruments which automatically render the dynamics of the composition from expression perforations in the music-sheet,—and comprises the improvement that said means is controllable at the will of the operator so that it 15 will render the dynamics as before, up to but not beyond a limit which is less than the maximum degree of loudness producible from said expression perforations. This ability to limit the maximum loudness of 20 tone is a feature which it is desirable to use under various conditions and situations. The specific embodiment of my improvements as shown herein permits the operator to apply and remove the limiting device at 25 any time before or during the rendition without any possible injury to the other mechanism.

In the drawings, which illustrate only one 30 of the specific embodiments my invention may take, although the one I prefer at this time,—Figure 1 is a side-elevation of the dynamics-expression mechanism of a reproducing-piano with my maximum-dynamics limiting improvements applied thereto; 35 said view also showing diagrammatically the music-sheet, tracker-bar and connections; Fig. 2 is the same except that the limiting device is shown in its inactive position; Fig. 3 is a horizontal section partly in 40 plan on the line 3—3 in either Fig. 1 or 4; and Fig. 4 is a vertical section partly in elevation on the line 4—4 in Fig. 3 looking in the direction of the arrows.

I will now describe the illustrated specific 45 embodiment of my invention:—1 is a rigid-walled box having its bottom 2 hinged thereto at 3, said bottom being united by flexible sides 4 to the box 1 so that the whole forms a bellows; in fact forms a so-called 50 expression- or regulating-bellows as will hereinafter appear. 5 is a pipe connecting as usual the player-action of the automatic

piano with the interior of the regulating-bellows. 6 is a block secured in the position shown in Figs. 3 and 4, inside the box 1. 7 55 is a port in the front face of this block connected by the angular passage 8 in the block 6, with a tubular-connection 9 which latter in turn is connected with the usual exhauster or air-tension producing apparatus or 60 source. The valve 10 controls the aforesaid port 7 in the block 6. The heel of this valve pivots on a pin 11 of the arm 12 secured to the rock-shaft 13, said shaft having a bearing 14 on the rear-wall of the box 1, across 65 which latter it extends and thence through bearing 15 to the outside where the arm 16 is secured to said shaft.

The toe of this valve 10 is connected by a 70 link 17 with the movable-board 2 of the bellows. 20 is a spiral tension-spring connecting the movable-board of the regulating-bellows with the fixed arm 21. 18 is a washer and 19 a leaf-spring on the pin 11, the ends of said spring bearing against the 75 valve 10 to keep its working-face seated against the face of the block 6.

The arm 16 is connected by a link 22 with the so-called accordion-bellows 23. This consists of a plurality of separate bellows, *a*, *b*, 80 *c*, *d*, secured together in a stack, one on top of another. The bottom 24 of the stack is secured to a fixed support. 25 are independent, tubular connections with the respective compartments *a*, *b*, *c* and *d* of the accordion-bellows. These connections or nipples 25 are in turn operatively connected with their respective ducts in the tracker-bar 27 (Fig. 1) by means of tubing 29 and valve-boxes 30 in the well-known manner in this art. 85 The tension-spiral spring 26 (Fig. 2) pulling on the arm 16 and link 22 keeps the accordion-bellows normally expanded. When 90 the dynamics expression-perforations in the music-sheet open the aforesaid tracker-ducks, the related compartment or compartments of the accordion-bellows is or are collapsed. These compartments have different extents of collapse, *d* being the largest, decreasing to the smallest *a*; and further they 95 can be collapsed from the expression-perforations 28^a in the music-sheet 28 either singly, or in any combination or all together. As is well-known in the art, this makes it pos-

sible from said expression-perforations to adjust the arm 16 into many different positions and therefore the heel of the valve 10 also into many different positions.

5 In Fig. 4, the full lines show the heel of the valve in its uppermost position brought about whenever there are no expression-perforations in the music registering with the tracker-ducks, with the result that all 10 of the compartments of the expression-bellows are fully expanded and the spring 26 pulls the heel of the valve into the full-line position shown.

15 The dotted lines in Fig. 4 show the heel of the valve in its lowest position brought about by the collapse of all the compartments of the accordion-bellows due to all four of the ducts 27^a in the tracker-bar being opened by expression-perforations 20 in the music-sheet. Between these extreme positions of the heel of the valve, there will be many intermediate positions dependent only upon the number of different combinations possible in the expression-perforations 25 28^a.

It is well understood in the art, that a regulating-bellows when in action constantly tends to collapse until its valve closes the passage through the bellows or 30 substantially so. Thus in Fig. 4, when the heel of the valve is in the uppermost position, the regulating-bellows will automatically collapse until the valve approximates the full line position with the port nearly 35 or quite closed. Also the movable-board 2 of the bellows will approximate the full line position in Fig. 4. Also the spring 20 will be only slightly tensioned thereby. All 40 of which means that the pneumatic-tension maintained in the playing-action by the ex- 45 hausters via the regulating-bellows will also be slight and all notes will sound pianissimo when the heel of the valve is in said assumed uppermost position.

45 The reverse is true when the heel of the valve is in its lowest or dotted position in Fig. 4 because then in order to close the valve, the movable-board 2 of the regulating-bellows must move all the way up to 50 the dotted position designated 2, putting the spring 20 to its maximum stretch and tension. To do this requires maximum air-tension in the regulating-bellows; and accordingly this same degree of air-tension is 55 transmitted and maintained by said bellows in the player-action so that all notes then played will sound maximum loud. Intermediate adjustments of the heel of the valve by the accordion-bellows and music-sheet as 60 aforesaid result in putting the spring 20 under correspondingly intermediate degrees of tension; and in varying the dynamics of the playing accordingly.

By the foregoing, the whole range of

dynamics including the entire upper limit, 65 will be rendered. But not infrequently it is desired to render the composition without the maximum dynamics in spite of the fact that the expression-perforations in the music-sheet call for it. This I accomplish by 70 means as follows:—31—32 are a pair of toggle-arms, 32 being pivoted at 33 to the lower-end of a stationary metal strip 34 which above is screwed to the side of the box 1. The upper-end of the toggle-arm 31 is bent 75 over to form a foot 35. When the toggle is straightened as in Fig. 1, the foot 35 is in the path of the arm 16 and prevents it from descending to its lowermost positions, which in turn prevents the heel of the regulating- 80 bellows valve 10 from being carried beyond a moderately loud playing-position. In other words, the maximum loud passages will now be subdued to moderately loud—but all the dynamics will still be rendered 85 automatically from the music-sheet.

Fig. 2 shows the toggle broken, thereby carrying the foot or stop 35 out of the way of the arm 16 even when in its extreme, lowest position. In other words, the foot is 90 now out of operation and the instrument plays normally, that is with the full or maximum dynamics represented by the expression-perforations in the music.

The additional elements employed for 95 supporting and operating the toggle are the following:—36 is an arm pivoted at one end to the face of the box 1; and pivoted at its other end to the upper toggle-arm 31. The joint of the toggle is connected by a 100 link 37 with the lower end of a lever 38 pivoted at 39 to the box 1 and having its upper end connected by a link 40 with an operating hand-lever 41 pivotally supported at 42 so that its lower or handle-end swings 105 adjacent a tablet 43 marked "Normal" and "Soft." It will be seen from the above description of the mechanism that when the handle is at "Normal" as in Fig. 2, the toggle will be broken and out of action, so that 110 the instrument will play with the full dynamics of the expression-perforations; whereas when the handle of the lever 41 is at "Soft," the toggle will be straightened into the position shown in Fig. 1, and will 115 thereafter in the manner previously explained, automatically eliminate the maximum-loud playing effects.

The advantages of using a toggle-joint in this particular adaptation comprise the following:—When the toggle is straightened as in Fig. 1, the striking of the arm 16 against it does not tend to throw the parts out of position, and no additional locking means is required to keep them in said position. 120 Further the toggle can be operated during playing without fouling any of the other parts. Thus even while the arm 16 is in its

extreme lowest position with the instrument playing maximum loud, the toggle can be straightened without injuring or binding any part because its foot 35 will merely 5 push up under the end of the arm 16 lifting it into the position at which it is stopped by said foot.

Of course changes and modifications may be made in the foregoing embodiment of my 10 invention without departing from the spirit of the invention and of the annexed claims.

What I claim is:—

1. In a player-piano or the like, means for controlling the dynamics of the rendition 15 from expression-perforations in the music-sheet up to and including the maximum degree of loudness and also for so controlling the dynamics of the rendition up to a degree which is less than the maximum degree 20 of loudness producible by the expression perforations, comprising player actions, a source of air tension, an expression valve controlling the air tension on the player actions, an accordion bellows whose individual compartments have different extents 25 of collapse, said compartments being operable individually and permutatively from the expression perforations in the music sheet to operate the aforesaid valve step-by-step 30 from a minimum to a maximum extent to vary the dynamics accordingly, and a stop having means for manually interposing it at the will of the operator in a position which limits said adjustment of the 35 valve by the sheet-controlled adjusting means to an extent less than the maximum producible by the expression-perforations of said sheet.

2. In a player-piano or the like, means for controlling the dynamics of the rendition 40 from expression-perforations in the music-sheet up to and including the maximum degree of loudness and also for so controlling the dynamics of the rendition up to a degree which is less than the maximum degree 45 of loudness producible by the expression perforations, comprising player actions, a source of air tension, an expression valve controlling the air tension on the player 50 actions; a plurality of bellows severally operable from the expression-perforations in the music-sheet and adapted to adjust said valve step-by-step from a minimum to a maximum extent to vary the dynamics accordingly; and a stop which is interposable to limit the aforesaid adjustment of the 55 valve to an extent that is less than the maximum producible by the expression-perforations of said sheet.

60 3. In a player-piano or the like, means for controlling the dynamics of the rendition from expression-perforations in the music-sheet up to and including the maximum degree of loudness and also for so controlling

the dynamics of the rendition up to a degree 65 which is less than the maximum degree of loudness producible by the expression perforations, comprising player actions, a source of air tension, an expression valve controlling the air tension on the player 70 actions; a series of bellows severally operable from the expression-perforations in the music-sheet and connected to said valve to operate it step-by-step from a minimum to a maximum extent to vary the dynamics accordingly, 75 and a stop having means for manually interposing it in a position to limit the action of said tension-adjusting means to an extent which is less than the maximum producible by the expression-perforations of the music-sheet.

4. In a player-piano or the like, means for controlling the dynamics of the rendition 80 from expression-perforations in the music-sheet up to and including the maximum degree of loudness and also for so controlling the dynamics of the rendition up to a degree which is less than the maximum degree of loudness producible by the expression perforations, comprising player actions, a 85 source of air tension, an expression valve controlling the air tension on the player actions, a series of bellows severally operable from the expression perforations in the music sheet and connected with said valve 90 to operate it step-by-step from a minimum to a maximum extent to vary the dynamics accordingly, a stop interposable at the will of the operator which limits said adjustment of the valve by the sheet-controlled 95 adjusting-means to an extent less than the maximum producible by the expression-perforations of said sheet; and a toggle for bringing said stop into and out of stopping-position, the arms of the toggle being substantially in alinement when the stop is in stopping position.

5. In a player-piano or the like, means for controlling the dynamics of the rendition 100 from expression-perforations in the music-sheet up to and including the maximum degree of loudness and also for so controlling the dynamics of the rendition up to a degree which is less than the maximum degree of loudness producible by the expression perforations, comprising player actions, a 105 source of air tension, an operative regulating-bellows having a valve-controlled passage therethrough connecting the air-tension source with the player-action, the valve being operatively connected with the movable-board of said bellows; means automatically operated from the expression-perforations in the music-sheet for varying the tension on the movable-board of the regulating bellows, tending to open the valve from its closed position; a stop which is interposable to limit the action of said tension-varying 110 115 120 125

means to the production of a tension on said movable-board which is less than the maximum producible by the expression-perforations of the music-sheet; and a toggle for bringing said stop into and out of stopping-position, the arms of the toggle being substantially in alinement when the stop is in

position with the stopped-part acting against them.

In testimony whereof I, said JOSEPH HUNTER DICKINSON, have signed my name to this specification, this 26 day of August 1918.

JOSEPH HUNTER DICKINSON.
